United States Patent Office

Des. 215,863
Patented Nov. 4, 1969

215,863

STAND FOR TREES

James E. Fisher, Jack L. Mitchell, and Gerald F. Wisdom,
Sterling, Colo., assignors to Tiger Products, Inc., Sterling,
Colo., a corporation of Colorado

Filed Jan. 8, 1969, Ser. No. 15,257

Term of patent 14 years

Int. Cl. D11—02

U.S. Cl. D35—3

FIG. 1

FIG. 4

FIG. 5

FIG. 2

FIG. 3

FIGURE 1 is a perspective view of a stand for trees showing our new design;

FIGURE 2 is a top plan view of the stand for trees shown in FIGURE 1;

FIGURE 3 is a bottom plan view of the stand for trees shown in FIGURE 1;

FIGURE 4 is an elevational view of the stand for trees taken along line 4—4 of FIGURE 2; and

FIGURE 5 is an elevational view of the stand for trees taken along line 5—5 of FIGURE 2.

We claim:

The ornamental design for a stand for trees, as shown.
